UNITED STATES PATENT OFFICE.

JOHN KLEE, OF NEW YORK, N. Y.

FABRIC FOR WALL-DECORATION.

SPECIFICATION forming part of Letters Patent No. 324,941, dated August 25, 1885.
Application filed November 21, 1884. (Specimens.)

To all whom it may concern:

Be it known that I, JOHN KLEE, of the city, county, and State of New York, have invented certain new and useful Improvements in Wall-
5 Decorations, of which the following is a specification.

The object of this invention is to furnish an improved wall-decoration that is finished in the shop and then applied to the wall at the 10 point of use; and the invention consists of a wall-decoration composed of a backing of paper or other suitable material, an intermediate textile fabric, and a molded face layer of plaster-of-paris, or of other suitable material.

15 The invention consists, secondly, of a method of making wall-decorations by running plaster-of-paris or other suitable plastic material into a mold, placing a backing covered with a textile fabric over the same, removing the surplus of plastic material by pressure, and taking 20 the wall-decoration out of the mold when the plastic material has properly set.

In the accompanying drawings, Figure 1 represents a front elevation, and Fig. 2 a horizontal section on line x x , Fig. 1, of my improved wall-decoration.

Similar letters of reference indicate corresponding parts.

Referring to the drawings, A represents a 30 backing of paper, pasteboard, or other suitable material, by preference asbestos-paper, as this is less liable to be affected by the moisture of the walls. The backing A is covered by a layer, B, of textile fabric, preferably widely-

meshed canvas, and covered by a face layer, 35 C, of plaster-of-paris mixed with dextrine or other gum, or of any other suitable plastic composition.

In making my wall-decorations a mold with the required design is first prepared and the 40 plastic material run into the same in liquid state. The backing covered by the textile fabric is then placed over the plastic mass in the mold and pressed gently thereon, so as to remove the surplus of plastic material. The 45 mass is then allowed to set in the mold and is removed with the backing. The wall-decoration is applied to the wall by any suitable cement used by stucco-workers, the joints being also filled with cement, so as to obtain a 50 continuous and ornamental wall-covering.

Wall-decorations can thus be made in any design and color, prepared in the shop, and then put up on the walls at the point of use.

Having thus described my invention, I claim 55 as new and desire to secure by Letters Patent—

A wall-covering composed of a backing of paper or other suitable fabric, an intermediate textile fabric, and a layer of plaster-of-paris or other suitable plastic material, substantially as set forth.

In testimony that I claim the foregoing as my invention I have signed my name in presence of two subscribing witnesses.

JOHN KLEE.
